[57] CLAIM

The ornamental design for an oil container or the like, as shown and described.

DESCRIPTION

FIG. 1 is a front elevational view of an oil container or the like showing my new design;
FIG. 2 is a left side elevational view thereof;
FIG. 3 is a top plan view thereof; and
FIG. 4 is a bottom plan view thereof.
The rear elevational view (not shown) is a mirror image of FIG. 1.
The right side view (not shown) is a mirror image of FIG. 2.
